UNITED STATES PATENT OFFICE.

JOHN L. DRAKE, OF TOLEDO, OHIO, ASSIGNEE TO THE LIBBEY-OWENS SHEET GLASS COMPANY, OF TOLEDO, OHIO, A CORPORATION OF OHIO.

SHEET-GLASS-DRAWING APPARATUS.

Application filed August 2, 1926. Serial No. 126,602.

The present invention relates to improvements in sheet glass apparatus, and has more particular reference to a novel draw table and driving mechanism therefor.

An important object of the invention is to provide a draw table for use in sheet glass apparatus, so constructed that it will present a substantially unbroken surface upon which the sheet may be supported without injury.

Another object of the invention is to provide a draw table having associated therewith, means for positively driving the same so that any danger of the draw table slipping will be reduced to a minimum.

Another object of the invention is to provide such an improved draw table embodying a plurality of substantially solid portions extending the entire width of the draw table, and a plurality of open portions alternately arranged, with the substantially solid portions.

Another object of the invention is to provide a draw table for use in sheet glass apparatus comprising a plurality of closely associated links and a plurality of spaced links pivotally connected with the closely associated links whereby to provide a substantially unbroken surface upon which the sheet of glass may be supported, said draw table being driven by means of a sprocket or the like engaging the spaced links.

Other objects and advantages of the invention will become more readily apparent during the course of the following description when taken in connection with the accompanying drawings.

In the drawings wherein like characters of reference have been employed to designate corresponding parts throughout the several views:

Fig. 1 is a vertical longitudinal section through a portion of a sheet glass drawing apparatus illustrating my improved device associated therewith,

Fig. 2 is a transverse section through a portion of the draw table and the driving mechanism therefor,

Fig. 3 is a perspective view of a portion of the draw table,

Fig. 4 is a plan view of a portion of the draw table shown in Fig. 3,

Fig. 5 is a similar view showing a somewhat modified type of link, and

Fig. 6 is a similar view showing a still further modified form of the invention.

In the Colburn machine set forth in the Colburn Patent 1,248,809, granted Dec. 4, 1917, a sheet 10 is continuously drawn from a mass of molten glass 11, contained in a draw pot 12. This sheet is initially drawn in a vertical plane, after which it is deflected laterally over a roll 13 and then passed over an idler roll 14. A draw table is used in connection with the clamp bars 15 to draw the sheet and to flatten the same. A suitable lip tile 16 and lip tile cooler 17 are provided to assist in properly conditioning the glass to permit the sheet to be drawn from the draw pot 12, and edge engaging means 18 are provided to make it possible to draw a sheet continuously from a mass of molten glass without narrowing at its base. The clamp bars 15 are so constructed that they engage or clamp the edges formed by the edge engaging means 18, and are driven by means of the sprockets 19. The sheet is then permitted to pass through an annealing leir, after which it is cut up into commercial sizes as will be readily understood. The annealing leir and cutting apparatus are not shown in the drawings.

The type of draw table disclosed in the Colburn patent comprises a plurality of straight sided links, being so constructed that a relatively large gap is formed between adjacent links. This type of draw table has not been found entirely satisfactory as the sheet of glass supported upon the draw table is comparatively soft so that it is susceptible to any surface distortion. Being soft, the glass will have a tendency to sag within the gaps between the ends of adjacent links, thus creating surface irregularities in the sheet. In addition to the tendency to sag in the gaps, hot gases are permitted to blow up against the sheet forming puffed places.

In Fig. 1 the numeral 20 designates the draw table in its entirety, and it is composed of a plurality of interlocking links so constructed as to produce an endless belt formation. Arranged within the loop of the draw table 20 and adapted to support the same in its upper horizontal run, are suitable draw table rails 21 supported upon beams 22.

The draw table 20 is adapted to be rotated by means of sprockets 23, mounted upon shafts 24 and keyed thereto by the

locking keys 25. A roll 26 is used to contact with the lower run of the draw table to keep the draw table taut.

In Figs. 3 and 4, it will be noted that the draw table embodies in its construction a plurality of closely associated links 27 and a plurality of spaced links 28. Each of the links 27 comprises a body portion 29 provided at its opposite ends with reduced apertured ears 30 and 31, said ears being disposed equi-distant from the opposite edges of the body to define shoulders 32, and these shoulders are approximately one-half the width of the ears 30 and 31. The links 27 are adapted to abut against one another in order to present a substantially solid surface extending the entire width of the draw table, and the adjacent ends of the links 28 are received within the spaces between the ears 30 and 31. The links 28 are spaced from one another and each of said links consists simply of a flat substantially rectangular bar having curved ends. The pivot pins 33 are passed through the ears 30 and 31, and the adjacent apertured ends of the links 28. In driving the draw table, the teeth 34 of the sprockets 23 will be received between the spaced links 28 so that the draw table will be positively driven, and any danger of the same slipping will be reduced to a minimum. As shown in Fig. 2, the sprockets 23 extend transversely the entire width of the draw table so that a uniform driving action will be imparted to the draw table throughout its entire width.

In Fig. 5 has been shown a slightly modified form of construction wherein the closely associated links 35 are provided at their opposite ends with notches 36, which result in the formation of ears 37, said ears being in alignment with one another at one side of the longitudinal axis of the link. The adjacent ends of the spaced links 28 are adapted to be received within the notches 36, and pivot pins 38, passing through the ears 37 and adjacent ends of the links 28, serve to pivotally connect the said links together.

In Fig. 6, a still further modified form of draw table has been shown, and in this form of the invention there are provided a plurality of transversely extending plates or bars 39 which are alternately arranged with the spaced links 28. Each of the bars 39 is provided along its longitudinal edges with spaced ears 40, and the adjacent ends of the links 28 are received within the spaces between these ears. Pivot pins 41, passing through the ears 40 and adjacent ends of the links 28, serve to pivotally connect the links together.

It will be thus seen that in all three forms of the invention set forth above, there is provided a draw table embodying a plurality of substantially solid portions, and a plurality of open portions arranged alter-

nately with the solid portions. The draw tables provided by the present invention will present a substantially unbroken surface upon which the sheet may be supported without injury, and in addition thereto means is provided for positively driving the draw table so that danger of slipping thereof is reduced to a minimum.

It is to be understood that the form of the invention herein shown and described is to be taken as the preferred embodiment thereof, and that any such modifications as properly fall within the scope of the appended claims may be resorted to without departing from or sacrificing the spirit of the invention.

Claims:

1. In sheet glass apparatus, a draw table having substantially solid portions and open portions, said substantially solid portions extending the entire width of the draw table, and means for driving the said draw table.

2. In sheet glass apparatus, a draw table having substantially solid portions and open portions, said substantially solid portions extending the entire width of the draw table, and means engaging the open portions for driving the said draw table.

3. In sheet glass apparatus, a draw table having substantially solid portions and open portions, said substantially solid portions extending the entire width of the draw table, and a sprocket for driving said draw table.

4. In sheet glass apparatus, a draw table having substantially solid portions and spaced portions, said substantially solid portions extending the entire width of the draw table, and a sprocket engaging the spaced portions for driving said draw table.

5. In sheet glass apparatus, a draw table having substantially solid portions and spaced portions alternately arranged, said substantially solid portions extending the entire width of the draw table, and a sprocket engaging the spaced portions for driving said draw table.

6. In sheet glass apparatus, a draw table including a plurality of closely associated links and a plurality of spaced links, and means for driving said draw table.

7. In sheet glass apparatus, a draw table including a plurality of closely associated links, and a plurality of spaced links, and means engaging the spaced links for driving said draw table.

8. In sheet glass apparatus, a draw table including a plurality of closely associated links, and a plurality of spaced links, and a sprocket for driving the said draw table.

9. In sheet glass apparatus, a draw table including a plurality of closely associated links and a plurality of spaced links, and a sprocket engaging the spaced links for driving said draw table.

10. In sheet glass apparatus, a draw table

- including a plurality of links closely associated to form a substantially solid surface, a plurality of spaced links, and a sprocket, the teeth of which are received between the spaced links for driving said draw table.
11. In sheet glass apparatus, a draw table including a plurality of links closely associated to provide a substantially solid surface and a plurality of spaced links arranged alternately with the closely associated links. ¹⁰
- Signed at Toledo, in the county of Lucas and State of Ohio, this 31st day of July, 1926.

JOHN L. DRAKE.
